UNITED STATES PATENT OFFICE.

CHARLES L. DEPOLIER, OF NEW YORK, N. Y.

EXPANSION-LINK CATCH-HOOK.

1,088,549.

Specification of Letters Patent. Patented Feb. 24, 1914.

Application filed May 6, 1913. Serial No. 765,683.

To all whom it may concern:

Be it known that I, CHARLES L. DEPOLIER, a citizen of the United States, residing in the city of New York, county of Kings, and State of New York, have invented certain new and useful Improvements in Expansion-Link Catch-Hooks, of which the following is a specification.

My invention in expansion link catch-hoops relates to a type of expansion link, combined with a catch-hook, which is more particularly adapted to articles of jewelry, as for example, bracelets, constructed of ribbon made of leather, fabric, or metal, or chain bracelets, and to that type employed to secure a watch or watch holder in position on the wrist of the wearer. In this connection, it has particular reference to an expansion catch-hook, which may be readily introduced to the bracelet structure, whereby a degree of expansion and contraction of the bracelet is permissible.

The object of my invention is to provide a neat, durable and inexpensive device, which may be introduced in a bracelet structure, whereby elasticity is afforded, as well as the range of expansion and contraction thereby augmented.

The features characteristic of my invention, whereby I attain the objects thereof, is depicted in the drawings, referred to in the correlative appended descriptive matter thereof, and pointed out in the claims, which together, comprise the specification.

With reference to the drawings: Figure 1 is a side elevational view of my improved expansion link catch-hook, secured to, in the instance illustrated, the end of a fragment of a strap; a portion toward the end of the latter and up to the point at which it is fastened to the catch-hook being removed. Fig. 2 is a sectional elevational view of a part of the catch-hook alone, taken on the line X—X of Fig. 3. Fig. 3 is a sectional plan view thereof, taken on the line 2—2 of Fig. 2. Fig. 4 is a sectional end elevational view thereof, taken on the line 4—4 of Fig. 1. Fig. 5 is a similar view to that of Fig. 3, illustrating the catch-hook in an extended position, and its retracting spring compressed. Fig. 6 is a top plan view of the expansion link catch-hook and connected strap terminal, drawn upon a somewhat smaller scale than in the preceding figures. Fig. 7 is a rear plan view of my improved strap terminal member, and

a fragment of a strap connected therewith, drawn to the same scale as in the preceding figure, and Fig. 8 is a plan detailed view of my improved expansion link catch-hooks, illustrating their application to a strap watch-bracelet.

In the several figures, similar characters of reference designate the same or identical parts throughout where they occur, wherein, Fig. 1 refers to the entire expansion link catch-hook structure. This comprises a strap box 2, preferably of metal, a hook 3, an elongated link 4 integral with said hook 3, guide plates 5 integral with the box 2, guide pin 6, sliding guide pin 7 rigid with and preferably soldered to the link 4, and playing in the guide plates 5, and a spiral compression spring 8, together with a cover 9.

The box 2 is of a somewhat flattened diamond formation, having a bottom 10 of slight longitudinal curvature; the curve being in the direction of the hook 3. One end of the bottom 10 is intermediately slotted. This end is designated 12, and the opposite end 13 is of substantially the same formation and preferably of less width. Folded at substantially right angles from the bottom 10, are side walls 14. These have intermediate parallel portions 15, and converging end portions 16. The latter portions are provided with perforations 17, of sufficient diameter, to permit of the entrance of the guide pin 6, through the guide plates 5. The parallel portions 15 of the walls 14 have perforations 18 toward their free ends, which, together with the perforations 17, provide an expedient for securing by means of coupling pins, the cover plate 9, to the box 2, as will be more fully hereinafter explained.

The guide plates 5 are slotted longitudinally on their opposite inner faces, to form guideways 19. The slotting operation is preferably begun at the end, designated 20, and is executed along the inner walls thereof for substantially one half of the length thereof, and in such a manner as to leave shoulders 21, or stops. The sliding guide pin 7 is of a length, suitable to fit between the guide-ways 19 and play freely therein, in a longitudinal direction from the end 20 to the shoulders or stops 21.

The link 4 is formed preferably, together with the hook 3, of a strip of metal, bent and folded, to provide a longitudinal run 22, a lower terminal 23, an opposite termi-

nal bend 24, and an upper inner terminal bend 25, leaving an end free to form a lip or bill 26 for the hook 3, while the opposite end is secured to the run 22 preferably by 5 a soldering operation. Intermediate of the width of the run 22, and projecting outwardly, substantially at right angles therefrom, and at the terminal 23 is a finger-catch 27.

10 Within the link 4 is secured the sliding guide pin 7, preferably by soldering, and playing between the guide pin 6 and sliding guide pin 7 is the housed spiral compression spring 8. Cover plate 9 has a 15 perimeter substantially identical with that of the bottom 10. This is provided with an outer cross-bar or guard 28, beveled off on the ends, and intermediately notched, to form a recess 29, opposite the bill 26 of 20 the hook 3, and it is moreover provided with a slot 30, corresponding to the slot cut through bottom 10 of the box 2.

Corresponding to the walls 14 of the box 2, and integrally formed with, and projecting downwardly from the cover plate 9, 25 is a neck 31, adapted to interfit with the walls 14 interiorly.

32 designates a fragment of ribbon or strap, with which my improved expansion 30 link catch-hook is engaged, and to which it is secured. In the instance illustrated, the engaging end of the strap 32 is notched out parallel with the slot 30 to a width equal to that of the lateral spacing of the guide 35 plates 5 exteriorly, and of corresponding length to engage the end 20, and it is notched out on its opposite outer edges 33, to form recesses 34, interfitting the inner opposite sides and outer ends of the neck 31. 40 The end portion of the strap 32, thus fitted to the cover plate 9 is preferably cemented thereto, and is additionally secured through coupling pins 35 to the neck 31. By thus securing the strap 32 to the cover plate 9, 45 a substantial terminal for the strap is provided, which, when assembled with the box 2, presents an ornamental tip, or strap terminal.

The assembling and operation of my improved expansion link catch-hook is effected by first securing the strap 32 by its slotted terminal to the cover plate 9, by a suitable adhesive cement, by rivets or both cement and rivets. The coupling or guide 50 pin 6 having been removed from the end of the guide plate 5, the elongated link 4 is next introduced into the slotted portion of the box 2, then the link is slid back into the position shown in Figs. 1 and 3, and the 55 guide pin 6 is introduced through the perforation 17 and guide plates 5. The spiral compression spring having been placed in position in the link 4, the pin 6 may be secured to the guide plates 5 by heading it 60 over on the outside, by means of a suitable

punch which may be introduced through the perforations, and the box 2 and cover plate 9 are now suitably secured to each other.

Upon pulling the hook 3 outwardly, or 70 in a direction as indicated in Fig. 5 which operation is rendered expeditious by a thrust of the finger against the finger-catch 27, the sliding guide pin 7 will compress the spiral compression spring 8 while it is playing in 75 the guide-ways 19, and upon the release of the hook 3, or finger-catch 27 the reaction of the said spring will return the link 4 and sliding guide pin 7, and bring the base of the finger-catch 27 against the inner wall 80 of the end 13, when further action shall have been arrested, and the expansion link and catch-hook will be in its normal position.

When it is desired to attach the expansion link catch-hook to a strap watch-bracelet, 85 as for example, that as illustrated in Fig. 8, a strap, together with the attached cover plate 9 is placed in position, as illustrated in Figs. 1 or 4 to assemble with the box 2, whereupon, the end of the cover plate, designated 36 corresponding to the end 12 of the bottom 10 shall lie in proximity to the hook 3 and serve as a guard therefor. In this position, the cover plate 9 together with the strap may be secured to the box 2, by 90 passing a coupling pin or screw through each of the perforations 17 and 18, and neck 31, and into the inclosed strap ends.

When my improved expansion link catch-hook is employed as an expansion unit in 100 a bracelet structure, the finger-catch 27 extends uppermost, while the bill 26 of the hook 3, as well as cross-bar or guard 28, lies in contact with the wrist of the wearer. The office of the guard 28 is to prevent the 105 bill 26 of the hook 3 from bearing too sharply against the flesh, while the guard 28, having a larger surface, obviates disagreeable pressure, when the bracelet structure is under tension.

110 In the watch bracelet, illustrated in Fig. 8, illustrating the disposition of two of my expansion link catch-hooks, a limited amount of elasticity is afforded after the strap has been buckled around the wrist in the securing of the position of the watch involved, whereby a degree of comfort is afforded the wearer. It is obvious, however, that a number of these expansion links may be introduced at various points in the length of the 115 strap to further enhance the elasticity of the bracelet as a whole.

After the bill 26 has been introduced to the bow of the watch or other linking element, and the same has been snapped into 120 position, around the hook 3, and positioned between the ends 36 of the cover plate and 125 130 the ends 12 of the box, security of the engaged link, or watch-bow, with my improved link catch-hook is assured.

It is obvious than many minor changes may be made in the construction of my improved expansion link catch-hook without departing from the spirit of the invention, 5 as for example, it may be duplexed by uniting two of them end to end, whereby double expansion is afforded, and the same may be constructed in a variety of forms conducive to ornamentation, and moreover, it is inexpensive in construction, as well as simple in 10 operation. Furthermore, it provides an expedient for promoting elasticity for the usual type of inelastic bracelet structures, and

15 Having fully described my invention, I claim as new and desire to secure by Letters Patent of the U. S.—

1. In a combined catch-hook and expansion link, a box, provided with exterior upwardly extended and laterally spaced integral walls, and an outer wall, the latter being longitudinally and intermediately slotted, and provided with inwardly projecting integral flanges, comprising upwardly projecting inner walls, in alignment with the said slot, and having longitudinal grooves, disposed as guide-ways, formed from one end of the said flanges, and terminating in stops, in a direction toward the other extremity of the 25 said flanges, an integral link and catch-hook, provided with a guide-pin playing between the flanges and guide-ways, a stop pin passing through the upwardly projecting inner walls and the link, and a compression spring 30 between the guide-pin and stop pin, situated within the link, together with a corresponding cover plate, carried by the box.
2. In a combined catch-hook and expansion

link, a casing, a slotted housing formed within the central portion of the casing, a 40 spring retracted link and hook carried by said housing, a guide-pin secured to one end of the link, guide-ways formed within the housing, and a cover plate carried by the said casing.

3. In an expansion catch-hook, a casing, comprising a cover, a box, an intermediately situated and longitudinally movable spring retracted catch-hook, the hook overlapping the cover, and a transverse bar, disposed as 50 a hook-guard, integrally formed with the cover, together with means, co-acting with the cover and box, for securing the two together.

4. In a strap terminal expansion catch-hook, the combination with a strap end, of a box and a cover therefor, the strap end being secured to the box and cover, and housed therebetween, of a longitudinally situated spring retracted link, guided and playing 60 within the box, and having an integrally formed catch-hook, projecting from the box and overlapping the cover, of a transverse guard upon the cover, adjacent to the hook, of fastening devices penetrating the box, 65 cover, and strap end, and of a finger-catch, integral with the link, extending through the box, substantially as described.

In testimony whereof, I have signed my name to this specification in the presence of 70 two subscribing witnesses.

CHARLES L. DEPOLIER.
